FOREIGN PATENT DOCUMENTS

DE 32 13 420 A1 10/1983

FIG. 1 is a perspective view of my new laundry machine pedestal with drawer;

FIG. 2 is a front view thereof;

FIG. 3 is a top view thereof;

FIG. 4 is a right side view thereof, a left side view being a mirror image thereof;

FIG. 5 is a bottom view thereof;

FIG. 6 is a perspective view thereof, showing the drawer extended;

FIG. 7 is a rotated top view thereof;

FIG. 8 is a right side view thereof, a left side view being a mirror image thereof; and,

FIG. 9 is a rotated bottom view thereof.

The broken line showing of the top, sides, bottom, legs, as well as the drawer sides and interior, including dividers, seen in FIGS. 1-9, is included for the purpose of illustrating portions of the laundry pedestal with drawer and forms no part of the claimed design.
